UNITED STATES PATENT OFFICE.

EDWARD CHARLES MEISSNER, OF ST. LOUIS, MISSOURI.

DIRECT-ACTING ENGINE.

SPECIFICATION forming part of Letters Patent No. 637,810, dated November 28, 1899.

Application filed May 4, 1899. Serial No. 715,540. (No model.)

To all whom it may concern:

Be it known that I, EDWARD CHARLES MEISSNER, a citizen of the United States, residing at the city of St. Louis, State of Missouri, 5 have invented a certain new and useful Improvement in Direct-Acting Engines, of which the following is a full, clear, and exact description, such as will enable others skilled in the art to which it appertains to make and 10 use the same, reference being had to the accompanying drawings, forming part of this specification, in which—

Figure 1 is a longitudinal sectional view through my improved direct-acting engine, 15 showing the piston in its rearmost position. Fig. 2 is a similar view, the handle being omitted, showing the piston in its forward position. Fig. 3 is a similar view showing the piston in its extreme forward position. Fig. 20 4 is a view showing the rear face of the valve-block. Fig. 5 is a longitudinal sectional view through said valve-block. Fig. 6 is a view showing the front face of the valve-block. Fig. 7 is a cross-sectional view on line 7 7, 25 Fig. 5. Fig. 8 is a cross-sectional view on line 8 8, Fig. 5. Fig. 9 is a longitudinal sectional view through line 9 9 of Fig. 8. Fig. 10 is an edge view of a sleeve which is introduced into the rear end of the valve-block. 30 Fig. 11 is a cross-sectional view through said sleeve. Fig. 12 is a rear end elevational view of the barrel or cylinder. Fig. 13 is a longitudinal sectional view of said barrel or cylinder. Fig. 14 is a cross-sectional view through 35 said cylinder on line 14 14, Fig. 13. Fig. 15 is a cross-sectional view through said cylinder on line 15 15, Fig. 13. Fig. 16 is an elevational view showing the handle and a portion of the cylinder, the flange of the handle 40 being broken away to more clearly show the manner of locking the coupling-sleeve in position. Fig. 17 is a rear edge elevational view of the coupling-sleeve clamping the cylinder and handle together; and Fig. 18 is a 45 longitudinal sectional view through said coupling-sleeve.

This invention relates to a new and useful improvement in direct-acting engines of that class commonly known as "pneumatic hammers," in which a chisel or tool is loosely introduced into the nose of the cylinder for receiving impacting blows from the piston.

The engine is designed to be held in the hand of an operator and guided in its work. Fluid-pressure, usually in the form of compressed 55 air, is supplied to the engine through the medium of flexible hose or supply-pipe, which is connected to the outer end of the handle. A throttle-valve under control of the operator controls and regulates the admission of pres- 60 sure fluid to the engine.

The object of this present invention is to construct an engine of the character described which is simple, cheap, and effective in operation and one which is free from vibrations 65 usually present in engines of this class, which vibrations render the handling of the tool by the operator extremely tiresome and difficult.

In an application filed by me on or about December 13, 1898, Serial No. 699,117, I have 70 shown and described an engine such as is illustrated in the accompanying drawings, and this present application may be said to relate particularly to the construction of the controlling-valve for admitting and exhaust- 75 ing pressure to and from the spaces at the rear end of the piston and its controlled ports. For a better understanding of the engine shown and described in my former application I will now describe the construction of the same and 80 the manner in which my improved valve operates therewith.

In the drawings, *a* indicates a handle provided with a suitable inlet duct or port, through which the pressure is supplied to the 85 engine. This port terminates at the outer end of the handle, and a threaded opening *b* is provided for the attachment of the hose or suitable nipple.

c indicates a thimble threaded into the base 90 of the handle and across a live-pressure chamber *d*, said thimble receiving a sliding throttle-valve *e*, which is held in a closed position by a spring *f*. A rod *g*, slidably mounted in the handle, bears against the 95 valve *e* at one end, and a lever *h*, pivoted at *i*, bears against the other end of rod *g*. The spring *f*, which tends to hold the throttle- valve home, bears at its other end against a nut *j*, which is interiorly threaded in the 100 thimble *c*. Nut *j* is provided with an outwardly-extending stem *k*, angular in cross-section, which is received in a correspondingly-shaped opening in a cap-piece *l*, which

is held in its outer position by a spring *m*, interposed therebetween and the nut *j*. A pin *n*, introduced into the outer end of thimble *c* after the parts are assembled, bears against the outer face of the flange on the inner end of the cap-piece and fits in suitable notches *o*, provided in the outer face of said flange, whereby when said cap-piece is pressed inwardly it slides on stem *k* and being disengaged from the pin *n* is capable of being turned to adjust the nut *j* inwardly or outwardly, which adjustment regulates the amount of travel, and consequently the available area, of the throttle-valve. When pressure is released from the cap-piece, the spring *m* forces the same outwardly and causes an engagement between one of the notches thereof and the pin *n*, which prevents accidental rotation of the parts.

20 A by-pass *p* is provided within the thimble *c* to conduct pressure behind the throttle-valve for the purpose of balancing said valve when in an open position, so that the same may be easily operated by its spring, and also 25 for assisting in holding said valve in a closed position.

The supply-duct *d* is located to one side of the slot *q*, in which the lever *h* is mounted, and opens into a concentric groove *r* in the 30 handle-base. The handle-base is provided with an interiorly-threaded flange *s*, which engages a collar or coupling-sleeve *t*, whose forward end is provided with an inturned flange *u*, fitting under a ring or flange *v*, 35 formed at the rear end of the cylinder. The valve-block or that part of the engine which receives the piston-controlling valve is clamped between the handle-base and the end of the cylinder by means of this coupling-sleeve, and in order to lock the coupling-sleeve in its home position and prevent accidental unscrewing thereof, which would seriously affect the operation of the engine, I 40 notch or form a series of serrations *w* on the rear edge of this coupling-sleeve, as shown more clearly in Figs. 16, 17, and 18, and mount in the flange *s* of the handle a spring-pressed pawl or dog *x*, which is permitted to ride over said serrations when the 45 collar is being screwed home and which prevents the accidental unscrewing of said collar. This dog *x* is mounted on a stem, around which is wound a torsional spring *y*, one end of said torsional spring entering the flange 50 and the other end the stem or a cap-piece *z*, arranged on the outer end of the stem and by which the same can be turned to raise the dog out of engagement with the serrations on the end of the coupling-sleeve whenever it 55 is desired to unscrew the said sleeve. The operation of this dog is shown more clearly in Figs. 1 and 16.

I will now describe the port arrangements and the manner in which pressure is admitted to the piston and its controlling-valve.

The cylinder or barrel, which I have marked 60 as an entirety, is bored to two different

diameters, the larger of which receives the head 21 of the piston and the smaller the body portion 22 of said piston, said body portion having a reduced annulus 23. When the chisel-shank is in position, the piston moves forward and delivers an impacting blow, being arrested at such forward movement at practically the point indicated in Fig. 2. Ports 24, 25, and 26 open into the forward end of the larger bore of the cylinder near the shoulder or the beginning of the smaller bore, these ports registering with corresponding ports 27, 28, and 29, formed in the valve-block and which open at their rear ends into the live-pressure chamber or concentric groove *r*. Pressure is thus conducted under or in advance of the larger head of the piston and tends at all times to force said piston rearwardly. In other words, there is a constant pressure in advance of the piston and an intermittent pressure behind the larger head of the piston. This intermittent pressure is controlled by a valve 30, preferably centrally arranged relative to the valve-block, said valve being of two different diameters, the larger, which I have marked 31, being on the forward end of the valve, while the smaller, 32, forms the rear end of the valve. These two portions of the valve are divided by an enlarged head or flange 33, which operates in what may be called the "largest" bore 43 of the valve-block. This valve-block, as shown more clearly in Figs. 5 and 9, is bored to three different diameters, the largest of which receives a sleeve 35, (in the rear end of the valve-block,) and the bore of this sleeve forms a chamber in which the smallest diameter 32 of the valve operates. The central head of the valve operates in the bore 34 of the valve-block, as above described, while the larger body portion of the valve operates in the smallest bore 36 of the valve-block. 100 Sleeve 35 has a seat formed in its rear end, in which is received a solid plate 37, while the valve-block and sleeve are formed with radial openings registering with each other, which I have marked 38, said openings leading to an exhaust space or chamber 39, formed between the flange of the handle-base and valve-block, said chamber communicating with the atmosphere through openings 40. Valve 30 is formed with an axial opening 41 110 extending entirely through the same, which opening when the valve is moved forwardly serves to exhaust pressure from the rear end of the cylinder, said pressure escaping through the openings 38, which are unclosed when 115 the valve is in such forward position. When the valve is thus forward, the body portion 31 projects a little distance into the cylinder and is designed to coöperate with a stem 42 on the piston, to be hereinafter described. 120 Each of the ports 27, 28, and 29 open into the bore 36 of the valve-block through ports 43, which ports 43 are opened and closed by the larger body portion 31 of the valve in its re-

ciprocation. Leading from the rear end of the bore 34 of the valve-block is a duct or passage 44, which opens into the smaller bore of the cylinder near its rear end, said passage 5 being opened or closed by the forward end of the piston by its reduced annulus 23, which annulus in one position of the piston admits pressure into the bore 34 and in another position of the piston establishes communication 10 between the duct 44 and the exhaust-opening 45 in the cylinder, located slightly in advance of the port 44. In order to accommodate the displacement of air in the bore 34 in front of the head of the valve, I provide 15 a port 46 and which opens into the exhaust-chamber 39 through a groove 47, as shown more clearly in Figs. 8 and 9. This port 46 serves no purpose except to relieve the valve of pressure in front of its head 20 when the same moves forwardly and to admit air at atmospheric pressure when the valve moves rearwardly.

The operation of the engine as above described is as follows: Assuming the parts to 25 be in position as shown in Fig. 1 and pressure admitted to chamber *d*, when lever *h* is moved forwardly it will unseat the throttle-valve to admit pressure to the annular chamber *r*, from which chamber pressure is conducted through to ports 27, 28, and 29 in registration with the ports 24, 25, and 26 and admitted into the larger bore of the cylinder near the forward end thereof. Under such 30 conditions the tendency of the piston is to move rearwardly, and in so doing the stem 42 contacts with the forward end of valve 30 and forces said valve rearwardly, so as to close the exhaust-ports 38 and open the inlet-ports 43 to admit pressure behind the piston. The 35 piston now moves forward, as the area of the rear end of the piston exceeds the area of the shoulder, being the difference between the larger and smaller bores of the cylinder, said forward movement continuing until the reduced annulus 23 opens the port 44 to pressure, which port admits said pressure behind the head of the valve, causing said valve to move forward, as shown in Fig. 2. The forward end of the piston now delivers an impacting blow on the shank of the chisel introduced into the end of the cylinder, after which the pressure behind the piston exhausting through the axial bore 41 of the valve, 40 the exhaust-passages 38, the exhaust-chamber 39, and into the atmosphere through the openings 40 will permit the pressure in front of the larger head of the piston to move said piston rearwardly until its stem 42 contacts with the forward end of valve 30 and moves 45 said valve rearwardly to close the exhaust-passages 38 and open the inlet-passages 43, as above described.

It is desirable in this class of engines to provide means whereby the piston will cease operating in the absence of the tool-shank without necessitating the operator closing the throttle-valve every time he changes the po-

sition of the tool with respect to the work being done, and to accomplish this I permit the piston to move forwardly to an abnormal position in the absence of the tool-shank, so as to open the ports 50, 51, and 52, being at the extreme forward ends of ducts 24, 25, and 26, and which in normal operation were in front of the larger head 21 of the piston, and also open ports 53, 54, and 55, leading from ports 24, 25, and 26, respectively, just to the rear of ports 50, 51, and 52. No pressure now being in front of the piston under these conditions the pressure behind the piston will hold it in such forward position until the tool-shank is again inserted to move the piston rearwardly to the position shown in Fig. 2 or to such position that the ports 50, 51, and 52 will be opened in front of the larger head 21 75 of the piston. It is obvious that when the piston is in its extreme position, as shown in Fig. 3, being its abnormal forward position, the valve 30 is in its rearward position and is admitting pressure behind the larger head 21 80 of the piston through the ports 43, which pressure can in some instances be relied upon to hold the piston forward and prevent its operation without resort being had to the openings 53, 54, and 55; but by reason of the possibility of accidental displacement of valve 30 from such rearward position, which might result in shutting off this pressure behind the piston and opening the exhaust of such pressure, I prefer to make the cessation of movement of the piston positive by providing the ports 53, 54, and 55. It will be seen that the exhaust behind the head of the valve is open to the exterior through the port 44 and, further, that accidental displacement of the valve 90 in the presence of the ports 53, 54, and 55 is prevented by reason of the constant pressure against the forward end of the valve. In the front end of the cylinder I prefer to introduce a hard-metal bushing or sleeve 56 to receive 95 the tool-shank. The forward end of the piston is also, preferably, provided with a groove 57, having notches 58, opening in front thereof, for the purpose of giving a lead to the valve-exhaust in advance of the rearmost position of the piston. Openings 59 are provided in the forward end of the cylinder back of the bushing 56 to admit the intake and outward passage of the air drawn in and forced out by the cylinder in its reciprocations. 100

It will be noticed that I have referred to several of the ports as being in triplicate for the purpose of admitting and exhausting a large volume of pressure fluid; but it is obvious that but one or more of such ports can 105 be used, if desired.

By having the body portions 31 and 32 of the valve of different diameters, the forward being the greater, said valve is thereby unbalanced, with a tendency at all times to force 110 said valve to the rear, which tends to relieve the valve of any injurious shocks or jars resulting from contact of the piston-stem 42 therewith. This increased area at the for-

ward end of the valve likewise holds said valve in its rearmost position when the piston is in its abnormal forward position, as shown in Fig. 3. This unequal area of the valve likewise prevents the valve from throbbing or floating and makes its movement in either direction positive.

I may also introduce a jam-nut 60 on the collar or coupling-sleeve to engage the flange 10 of the handle-base for the purpose of additional security, if desired.

I am aware that many minor changes in the construction, arrangement, and combination of the several parts of my device can be made 15 and substituted for those herein shown and described without in the least departing from the nature and principle of my invention.

Having thus described my invention, what I claim, and desire to secure by Letters Patent, is—

1. The combination with the handle-base and rotary coupling-sleeve, which latter is formed with a series of serrations or notches upon its rear end, of a spring-pressed dog 25 mounted in said handle-base for engaging said notches and preventing said coupling-sleeve from unscrewing, and a jam-nut mounted on said collar or coupling-sleeve, and engaging the handle-base; substantially 30 as described.

2. The combination with a handle-base formed with a flange *s*, of a valve-block abutting against said handle-base, a cylinder 20, provided with a flange *v*, at its rear end and 35 abutting against said valve-block, a collar or coupling-sleeve *t*, formed with an inturned flange *u*, at its front end, which co-operates with the cylinder-flange *v*, said coupling-sleeve having a threaded connection with the flange *s*, a jam-nut 60 threaded in the forward end of the coupling and impinging against the forward end of flanges *s*, and a dog *x*, engaging notches or serrations *w*, at the rear of said coupling-sleeve, and said dog being 40 mounted in the flange of the handle-base, and being provided with a spring for causing its engagement with the collar or coupling-sleeve; substantially as described.

3. The combination with a threaded flange 50 *s*, of a coupling-sleeve *t* carrying a jam-nut, both of which engage said flange, said coupling-sleeve being provided with notches or serrations on its engaging end, a dog *x*, pivotally mounted in the flanges, a torsional 55 spring for holding said dog in engagement with the coupling-sleeve, and a cap-piece fixed on the dog's spindle, by which the dog may be disengaged from the coupling-sleeve; substantially as described.

60 4. The combination with a cylinder bored to two different diameters, of a piston of corresponding diameters arranged in said cylinder, and a piston-controlling valve of two diameters, the larger of which projects into the 65 larger bore of the cylinder, whereby said valve is positively thrown in one direction by said piston, and a port for intermittently admit-

ting pressure at the other end of said valve; substantially as described.

5. The combination with a cylinder bored 70 to two different diameters, of a piston of corresponding diameters arranged therein, said cylinder being provided with ports for admitting constant pressure in front of the larger head of said piston, and a valve of two different diameters, the larger of which controls a port for intermittently admitting pressure behind the larger head of said piston, a central head on said valve, and a port which is controlled by said piston, for intermittently admitting and exhausting pressure behind the head of said valve; substantially as described. 75

80 6. The combination with a cylinder formed with two different diameters, of a piston arranged in said cylinder, the body portion of 85 said piston operating in the smaller diameter, and the larger head of said piston in the larger diameter, said head being connected to said body portion by a reduced shank, of a valve-block arranged at the rear end of said cylinder, said valve-block containing a valve of two diameters, and a central head, which operate in correspondingly-bored openings, a pressure-supply passage having a port which constantly opens in advance of the larger head 90 of the piston, and having a port which is controlled by said valve, which port intermittently admits pressure behind the larger head of the piston, and a port-opening behind the head of the valve, which port is controlled by 95 the piston; substantially as described.

100 7. The combination with a valve-block formed with an inlet-passage 27, port 42, exhaust-space 39, and port 44, of a hollow valve 30, provided with a head, and with an axial bore 41, which co-operates with the exhaust-passage when the valve is in a forward position, and a piston for positively moving said valve to the rear for closing said exhaust-passages and opening the inlet-port 42; substantially as described. 105

110 8. The combination with a cylinder formed with a bore of two diameters, of a piston of corresponding diameters arranged in said bore, a valve-block abutting against the rear end of the cylinder, a valve 30, slidably mounted in said valve-block, said valve having an opening throughout its length, the forward end of which valve projects into the cylinder-bore, a head on said valve, and suitable 115 port arrangements whereby pressure is constantly admitted to force the piston to the rear, the pressure behind said piston being exhausted through the hollow valve, the piston near the rear extremity of its stroke contacting with the valve to move the same rearwardly and open a live pressure-port to admit a preponderance of pressure behind the piston; substantially as described. 120

130 9. In a pneumatic hammer, the combination with a cylinder bored to two different diameters, with a shoulder between, a pressure-supply duct opening into the larger chamber near its forward end, a piston hav-

ing an enlarged head fitting in the larger bore, and a small body portion fitting in the small bore, said body portion having a reduced annulus, a valve comprising a small body portion at its rear end, a central head, and a larger body at its forward end which projects into the cylinder, and which is struck by the piston to be moved in one direction, and a port for intermittently admitting pressure behind the central head of said valve for throwing the same; substantially as described.

10. The combination with a cylinder formed with bores of two different diameters, of a piston arranged therein, a valve for controlling the admission of pressure to, and its exhaust from, the chamber behind the piston, said valve comprising a small body portion at its rear end, a central head, and a larger body at its forward end projecting into said chamber in one of its positions where it is struck by the piston and moved in one direction, a passage leading from behind the valve and opening into the piston-chamber by a port located in advance of the shoulder between the bores of the cylinder, which port is adapted to be opened and closed by the piston, an exhaust-port 45, in the cylinder in

advance of said last-named passage, said cylinder being likewise provided with a port- 30 opening 53, for admitting pressure behind the piston when said piston has moved forward beyond its normal operating position; substantially as described.

11. The combination with a cylinder bored 35 to two different diameters, of a piston operating in said cylinder, said piston having constant pressure in front of its larger diameter for forcing the same rearwardly, and a valve for intermittently admitting and exhausting a preponderance of pressure behind the larger diameter of the piston, said valve comprising a body portion of two diameters and a central head, said valve being also formed with an opening throughout its 40 length, and a port, which is controlled by said piston for admitting and exhausting pressure to and from behind said valve-head; substantially as described.

In testimony whereof I hereunto affix my 50 signature, in the presence of two witnesses, this 29th day of April, 1899.

EDWARD CHARLES MEISSNER.
